[57] **CLAIM**

The ornamental design for a front bezel and foot for a computer chassis, as shown and described.

DESCRIPTION

FIG. 1 is a right side elevation view of a front bezel and foot for a computer chassis showing my design. Features shown in broken lines are for illustrative purposes only and form no part of the invention.

FIG. 2 is a front elevation view of a front bezel and foot for a computer chassis showing my design. Features shown in broken lines are for illustrative purposes only and form no part of the invention.

FIG. 3 is a rear elevation view of a front bezel and foot for a computer chassis showing my design. Features shown in broken lines are for illustrative purposes only and form no part of the invention.

FIG. 4 is a top plan view of a front bezel for a computer chassis showing my design. Features shown in broken lines are for illustrative purposes only and form no part of the invention.

FIG. 5 is a left front isometric view of a front bezel and foot for a computer chassis showing my design. Features shown in broken lines are for illustrative purposes only and form no part of the invention; and,

FIG. 6 is a bottom rear right isometric view of a front bezel and foot for a computer chassis showing my design. Features shown in broken lines are for illustrative purposes only and form no part of the invention.
